UNITED STATES PATENT OFFICE

2,638,861

LOCKSEAMER FOR CORRUGATED
RADIATOR CORE BLANKS

Arthur G. Vogt, Toledo, Ohio

Application July 3, 1948, Serial No. 36,992

5 Claims. (Cl. 113—54)

1

This invention relates to the manufacture of radiator cores and particularly to cores used as a part of an automobile engine cooling system.

An object is to improve machines for lockseaming radiator core units to insure that the units are symmetrical and can fit together with other units in snug and intimate relationship, and finally to enable more efficient and satisfactory solder sealing of a plurality of such units.

Another object is to improve lockseaming machines for radiator core units so that the seamed ends of the units are substantially symmetrical at each corner, thereby to enable adjacent units to nest more closely together and to facilitate and make more uniform the subsequent sealing of the several core units.

Other objects and advantages of the invention will hereinafter appear, and for purposes of illustration but not of limitation, an embodiment of the invention is shown on the accompanying drawings, in which

Figure 1 is a top plan view of a lockseaming machine, a portion of the reciprocating ram being broken away for purposes of clarity, and the ram actuating mechanism being removed;

Figure 2 is a bottom plan view of the lockseaming die members, the rear portion of the supporting ram therefor being broken away;

Figure 3 is a side perspective view of the stationary longitudinally fluted arm showing a pair of core blanks mounted in position preparatory to lockseaming operation;

Figure 4 is a fragmentary side elevation of the arm shown in Figure 3, and showing particularly the ridged block;

Figure 5 is a transverse sectional view on the line 5—5 of Figure 4;

Figure 6 is a side elevation of that portion of the machine shown on Figure 1, but showing the ram in position preparatory to the lockseaming operation;

Figure 7 is an enlarged transverse sectional view substantially on the line 7—7 of Figure 6;

Figure 8 is a view similar to Figure 7, but showing the seaming dies advanced to effect a partial seaming of the radiator core strips or blanks;

Figure 9 is a transverse sectional view showing the lockseam completed and being flattened or ironed out; and

Figure 10 is a transverse sectional view showing a pair of lockseamed core units in nested relation.

The illustrated embodiment of the invention comprises a vertically disposed bracket 10 (Figure 6) which has a table-like top 11 of substantially rectangular form and pivotally mounted on

2

pins 12 are horizontally disposed arms 13 and 14 which are similar to each other. The arms 13 and 14 are elongate and are pivotally mounted approximately centrally thereof. At the rear end of each of these arms is an inwardly extending bracket 15 on which a roller 16 is mounted for rotation about the vertical axis. The rollers 16 engage opposite sides of a longitudinally reciprocating ram 17 which has a pair of oppositely disposed inwardly relieved surfaces 18. Suitably secured to the table 11 and extending upwardly therefrom is a support 19 for a horizontally disposed guide bar 20 which assists in guiding the reciprocating movement of the ram 17.

Mounted on the top of the table 11 in laterally spaced relation is a pair of arms 21 and 22 which project a substantial distance forwardly of the table 11 and are pivoted at their rear ends on pins 23 to the table. On the inner side of each of the arms 21 and 22, approximately midway of their length, are sockets 24 to receive the ends of a helically coiled spring 25 which tends to urge the arms 21 and 22 away from each other. On the forward end of each of the arms 13 and 14 is a set screw 26 which is adapted to be secured in adjusted position by a lock nut 27. It will be apparent that the coil spring 25 not only urges the arms 21 and 22 away from each other, but also through the set screws 26, yieldingly hold the rollers 16 in engagement with the sides of the ram 17. When the rollers 16 enter the relieved or depressed surfaces 18, the coil spring 25 separates the arms 21 and 22 sufficiently to enable the radiator core blanks to be inserted for the lockseaming operation, and also to enable the seamed unit to be removed as will hereinafter appear.

Rigidly mounted on the table 11 between the arms 21 and 22 is an arm 28 which is held in place by a pair of screws 29. As shown, the arm 28 is of approximately the same length as the arms 21 and 22 and the outer end portion of the arm 28 is of reduced thickness, particularly as shown in Figure 3. An enlarged opening 28a extending transversely through the central portion of the arm 28, accommodates the coil spring 25 which extends therethrough. Formed on the outer portion of the reduced end of the arm 28 is a longitudinal groove 30 on the upper side and each of the vertical sides is of corrugated form, providing a series of flattened ridges 31 and a series of grooves 32, the bottoms of which are flat. As particularly shown in Figures 7 to 9, the ridges and grooves alternate on opposite sides of the arm; that is, a ridge 31 on one side of the

arm has directly opposed to it a groove on the other side of the arm.

The inner sides of each of the pivoted arms 13 and 14 are similarly provided with a series of alternating ridges and grooves but the ridges and grooves of the arms 13 and 14 are so arranged that the ridges on the arms 13 and 14 are adapted to abut against the ridges on the stationary arm 28.

Carried at the forward end of the ram 17 is a plurality of die members which are adapted to lockseam the core blanks during the advancing movement of the ram 17. The members consist of a pair of substantially L-shaped die members 33 and 34 which are secured respectively to opposite sides of the forward end of the ram 17 and a die member 35 which has a triangularly disposed portion 36 which forms with the adjacent portions of the die members 33 and 34 the entering surfaces for the core blanks respectively. The die member 34 carries a presser plate 37 which projects rearwardly of the die members 33 and 34 to iron out or press the seam flatly into position as will hereinafter be described.

The detail construction of these die members forms no part of the present invention, lockseaming dies of this character being old in the art. Suffice it to say that two core blanks are placed in the machine substantially as shown in Figure 7, with their adjacent ends disposed in the path of travel of the ram 17, so that as the ram 17 advanced, the ends are progressively bent into lockseaming relation, and subsequently flattened and ironed out by the ironing die 37 as shown in Figures 7 to 9, the blanks, such as A and B, being gripped by the pivoted arms 13 and 14 against the stationary arm 28 due to the rocking movement of the arms 13 and 14 after the rollers 16 leave the relieved surfaces 18. The blanks A and B, particularly as shown in Figure 3, are formed with a series of laterally extending corrugations, the corrugations being such as to fit the ridges and grooves of the pivoted arms 13 and 14 (Figure 7).

Centrally of each core blank is formed a series of outwardly extending substantially pyramidal portions C and on the advanced edge portion of each blank is a series of outwardly extending substantially triangular box-like embossures arranged in series which open outwardly toward the side. At the opposite end are also embossures E arranged in series, it being understood that the series of embossures or projections of each blank cooperate with the other in forming a radiator core unit which when nested with others and properly sealed as by soldering, forms the radiator core structure.

One difficulty which has heretofore been experienced in machines of this character is in the proper location of the blanks A and B, it being understood that these blanks are of brass, copper or similar material which may be readily bent or formed to the desired configuration. In view of the thinness of the metal, the blanks may be deformed during the lockseaming operation and this difficulty is not infrequently encountered. In order to obviate that difficulty, a pair of inserts 38 is mounted on opposite sides of the stationary arm 28 and in this instance are held in place by pins or rivets 39. Each of the inserts is formed with a series of alternating V-shaped ridges 40 and grooves 41 of a configuration corresponding to the triangular box-like projections D so that the latter may fit over the respective

ridges which fill and support them during the lockseaming operation. To insure the proper position of the blanks, and particularly the box-like end portions D on the inserts, a stop pin 42 passes through the arm 28 and the inserts 38 and projects beyond the sides thereof a sufficient distance to engage the edges of the respective blanks A and B. The ends of the pin 42 serve as a stop and it is so positioned that the box-like portions D will have sufficiently fitted over the inserts adequately to support and obviate possible damage to them.

Another difficulty encountered in connection with the lockseaming operation is with respect to the outwardly extending corner portion as, for example, the corner portion 43, indicated in Figure 9. Ordinarily, in the bending of the blanks during the lockseaming operation and the subsequent ironing of the seam within the longitudinal grooves 30, the portion of the metal in the region of the bend 23 becomes displaced or deformed to such an extent as to militate against the proper joining of adjacent core units. To obviate this difficulty, a relatively small L-shaped finger 48 is carried by a slide 49. The slide 49 is provided with a pair of L-shaped slots 50 and studs 51 secured to the upper side of the pivoted arm 22 serve to guide the movement of the slide 49. Such movement is rearwardly and inwardly with respect to the arm 22, or forwardly and outwardly. For actuating the slide 49 is a link 52, the rear end of which is connected to an end portion of an arm 53 which is centrally pivoted on a pin 54 on the pivoted arm 22. On the opposite end of the arm 53 is an upstanding pin 55. The pin 55 when inoperative rides along a longitudinal groove or recess 56 formed in the ram 17. However, in operative position, the pin 55 engages in a notch 57 provided at the advanced end of the longitudinal recess 56.

In operation, when the ram 17 moves forwardly to effect the lockseaming operation, the pin 55 is engaged by a wall of the notch 57 and rocks the arm 53 to the dotted line position shown in Figure 45, 1, thereby retracting the slide 49 and moving the finger 48 into the position shown on Figure 3, thus to support the portion 43 (Figure 9). It will be observed that the finger 48 has its outer side inclining to correspond to the inclination of the blank A in that region and the top of the finger 48 is flat. The finger remains in that position during the lockseaming operation as well as the final ironing step so that the proper angularity of the blank A, as at 43, is retained. When the ram 17 retracts, it will be manifest that the slide 49 is shifted forwardly and outwardly away from the lock-seamed unit and remains in that position until the next succeeding advancing stroke of the ram.

It is to be understood that numerous changes in details of construction, arrangement and operation may be effected without departing from the spirit of the invention especially as defined in the appended claims.

What I claim is:

1. In a lockseamer machine for transversely corrugated radiator core blanks, blank folding die members, a reciprocable ram for carrying said blank folding die members, a pair of levers intermediately pivoted and actuated by said ram for effecting clamping movement thereof, a centrally disposed rigid arm and a pivoted spring-tensioned blank clamping arm on each side of said rigid arm movable by the adjacent lever, outwardly extending corrugated members on oppo-

site sides of said rigid arm against which the end portions of the blank fit, said members having corrugations corresponding to the adjacent portions of the blanks to be seamed, and stop means for positioning the blanks associated with said members.

2. The organization as claimed in claim 1, in which the outwardly extending corrugated members constitute separate parts and in which the stop means comprises a pin projecting through the corrugated members and the rigid arm with a portion beyond opposite sides of the members.

3. The organization as claimed in claim 1, in which the radiator core blanks to be lockseamed are formed with a series of outwardly extending triangular box-like projections and the outwardly extending corrugated members are of such configuration as to fit within such triangular box-like projections to sustain the shape thereof during the lockseaming operation.

4. The organization as claimed in claim 3, in which means is provided responsive to the movement of the ram for engaging a corner portion of a core blank to be lockseamed to hold same in position during the lockseaming operation.

5. The organization as claimed in claim 1, comprising a supporting finger for sustaining a corner portion of a core blank to be lockseamed during the lockseaming operation, and means responsive to the ram movement for actuating said finger to and from operative position.

ARTHUR G. VOGT.
